UNITED STATES PATENT OFFICE

165,360

COMBINATION CIGARETTE AND MATCH POUCH

Jules Brettner, Bronx, N. Y.

Application March 29, 1949, Serial No. 1,688

Term of patent 3½ years

(Cl. D85—2)

To all whom it may concern:

Be it known, that I, Jules Brettner, a citizen of the United States of America, residing at 735 Bryant Avenue, Bronx 59, New York, have invented a new, original, and ornamental Design for a Combination Cigarette and Match Pouch, of which the following is a specification, reference being had to the accompanying drawing, forming a part hereof.

In the drawing:

Fig. 1 is a front elevational view of a combination cigarette and match pouch showing my new design;

Fig. 2 is a side elevational view; and

Fig. 3 is a top plan view thereof.

The back of the pouch is plain except that it is overlain by a clip member as shown in Fig. 3.

I claim:

The ornamental design for a combination cigarette and match pouch, as shown and described.

JULES BRETTNER.
